UNITED STATES PATENT OFFICE.

MICHAEL RIESNER, OF CINCINNATI, OHIO, ASSIGNOR TO WORTHINGTON PUMP AND MACHINERY CORPORATION, A CORPORATION OF VIRGINIA.

AIR COMPRESSOR.

1,417,571.

Specification of Letters Patent. Patented May 30, 1922.

Application filed April 13, 1920. Serial No. 373,611.

To all whom it may concern:

Be it known that I, MICHAEL RIESNER, a citizen of the United States, residing at Cincinnati, county of Hamilton, and State of Ohio, have invented certain new and useful Improvements in Air Compressors, fully described and represented in the following specification and the accompanying drawings, forming a part of the same.

This invention relates to multistage air compressors, the especial object being to provide a high speed and high compression machine which shall occupy the minimum of floor space and otherwise shall be of compact construction, while at the same time simple and convenient of manufacture and capable of ready access to the different parts for upkeep, and of high efficiency and economy. The compressor has been designed for torpedo charging, but is applicable to other uses where a compact compressor, capable of operating efficiently at high speed and high compression, is required.

For a full understanding of the invention, a detailed description of a construction embodying the same in the best form now known to me will now be given in connection with the accompanying drawings, forming a part of this specification, and the features forming the invention then particularly pointed out in the claims.

In the drawings—

Figure 1 is a side elevation of the machine; Figure 2 is an end elevation looking to the left in Fig. 1, and with certain parts in section.

Figure 3 is a central section through the steam and air cylinders, longitudinally of the shaft, and

Figure 4 is an irregular section on the line 4—4 of Fig. 1 with the first stage compressor head partially broken away to show the valves and the first stage cooler in section.

Referring to the drawings, the piston for the first and second stages is a differential trunk piston having the head A and reduced trunk B operating in the first stage chamber a above the piston, and second stage chamber b around the trunk. C is the third stage piston operating in the third stage chamber c below it, and D is the fourth stage piston or plunger operating in the fourth stage chamber d above it.

The differential piston A, B is connected

directly by connecting rod 10 to steam piston E operating in cylinder F preferably arranged tandem to the first and second stages. The third and fourth stages are arranged at the side of the first and second stages, along the two-throw crank shaft G, the differential piston A, B being connected to its crank 11 by connecting rod 12, and the third and fourth stage pistons C, D being carried by a single rod 13 secured to cross head 14 which is connected to their crank 16 by connecting rod 15. The steam cylinder F may be provided with any suitable valve movement, a valve movement of ordinary type, actuated from the crank shaft G, being indicated.

The suction and discharge valves 1, 2 for the first stage are arranged in the cylinder head and the discharge is through pipe 17, intercooler formed by coils 18 in cooling chamber 19 and pipe 20 to suction valve 3 of the second stage, and the second stage delivers through its discharge valve 4, discharge pipe 21 and intercooler formed by coils 22 in cooling chamber 19 to suction valve 5 of the third stage, which delivers through its discharge valve 6, discharge pipe 23 and intercooler formed by coils 24 within cooling chamber 25 to the fourth stage through its suction valve 7, and this stage discharges through its discharge valve 8, pipe 26 and the aftercooler formed by coils 27 within chamber 25, to the final discharge 28. Each of the coolers is provided with a separating chamber 29 having blow-off valves for the collecting and discharge of any moisture precipitated within the coolers.

It will be seen that the invention provides a very simple, compact and convenient compressor, which is well balanced and capable of operating efficiently at a very high speed and high compression. For instance, the compressor shown is capable of running efficiently at a steam pressure of 250 pounds per square inch non-condensing, with a normal speed of 300 R. P. M., with delivery of about 20 cubic feet of air per hour at a pressure of 3,000 pounds per square inch. The arrangement of the coolers, and especially the placing of the first and second stage cooler coils in the water jacketed space of the low pressure air cylinder and preferably one above the other, reduces the floor space dimensions and length of piping, and this with the arrangement of the higher stages and

steam cylinder, reduces the floor space to a minimum. The mounting of the steam cylinder tandem with and above the differential piston with the higher stages at one side, reduces the overall height of the compressor, and this arrangement of steam cylinder avoids the use of an additional frame, connecting rod and cross-head, and is important in steam driven compressors. It will be understood, however, that air compressors in which the crank shaft is driven otherwise than by a steam cylinder, and in which less than four stages are used, may embody certain features of the invention as defined by the claims.

What I claim is:

1. In an air compressor, the combination with a two-throw crank shaft, of a differential piston and chambers forming the first and second stages of the compressor, a steam cylinder arranged above and having its steam piston connected directly to said differential piston, and one or more cylinders and pistons forming a higher stage or stages of the compressor arranged at the side of the steam cylinder and differential piston and connected to the crank shaft by a single crank.
2. In an air compressor, the combination with a two-throw crank shaft, of a differential piston and chambers forming the first and second stages of the compressor, a steam cylinder arranged above and having its steam piston connected directly to said differential piston, and third and fourth stage cylinders mounted in line vertically and at the side of the steam cylinder and differential piston, and having their pistons directly connected together and connected to the crank shaft by a single crank.
3. In an air compressor, the combination with a two throw crank shaft, of a differential piston and chambers forming the first and second stages of the compressor, a steam cylinder arranged in line with and having its steam piston connected directly to said differential piston, and third and fourth stage cylinders arranged in line vertically and at the side of the steam cylinder and differential piston, and having their pistons directly connected together and connected to the crank shaft by a single crank, said first and fourth stage pistons compressing upward and said second and third stage pistons compressing downward.
4. In an air compressor, the combination with a two throw crank shaft, of a differential piston and chambers forming the first and second stages of the compressor, and two cylinders and pistons forming the third and fourth stages of the compressor arranged at

the side of the differential piston and connected to the crank shaft by a single crank.

5. In an air compressor, the combination with a two throw crank shaft, of a differential piston and chambers forming the first and second stages of the compressor, and third and fourth stage cylinders mounted in line vertically and at the side of the differential piston, and having their pistons directly connected together and connected to the crank shaft by a single crank.

6. In an air compressor, the combination with a two throw crank shaft, of a differential piston and chambers forming the first and second stages of the compressor, and third and fourth stage cylinders arranged in line vertically and at the side of the differential piston and having their pistons directly connected together and connected to the crank shaft by a single crank, said first and fourth stage pistons compressing upward and said second and third stage pistons compressing downward.

7. In an air compressor, the combination with a differential piston and chambers forming the first and second stages of the compressor, of a cooling chamber forming an extension of the jacket space of the cylinder, and cooling coils for the first and second stages arranged one above the other in said chamber.

8. In an air compressor, the combination with a differential piston and chambers forming the first and second stages of the compressor, of a cooling chamber forming an extension of the jacket space of the cylinder and cooling coils for the first and second stages arranged one above the other in said chambers, one or more cylinders and pistons forming a higher stage or stages mounted on the crank shaft in line with the differential piston, a cooling chamber extending vertically along the higher pressure cylinder or cylinders, and a cooling coil or coils for the higher stage or stages in said cooling chamber.

9. In an air compressor, the combination with a differential piston and chambers forming the first and second stages of the compressor, of third and fourth stage cylinders and pistons arranged in line and with the fourth stage cylinder above, said third and fourth stage pistons being directly connected and connected to the crank shaft by a single crank, a cooling chamber extending vertically along the fourth stage cylinder, and cooling coils for the third and fourth stages in said cooling chamber.

In testimony whereof, I have hereunto set my hand.

MICHAEL RIESNER.
